ARTICLE OF JEWELRY

Louis Mazer, New York, N. Y.

Application April 20, 1934, Serial No. 721,445

7 Claims. (Cl. 63—1)

The invention relates to an article of jewelry and more particularly to an article of this nature in which the parts may be combined to form ornamental, distinctive and extremely good looking effects.

The article of jewelry broadly comprises a supporting member, a pair of ear clips, and ornamental bar and a dress clip. These parts may be combined or interchanged in various manners to form different pieces of jewelry as will become apparent in the following specification.

Referring to said specification and to the drawing forming a part thereof:

15 Fig. 1 is a perspective view of the supporting member;

Fig. 2 is a perspective view of the ear clip;

Fig. 3 is a perspective view of the ornamental bar;

20 Fig. 4 is a perspective view of the dress clip;

Fig. 5 is a front elevation showing the ornamental bar combined with the ear clips to form a brooch;

25 Fig. 6 is a rear elevation of the parts shown in Fig. 5;

Fig. 7 is an end view of the arrangement illustrated in Figs. 5 and 6;

Fig. 8 is a front elevation of the dress clip combined with the ear clips to form another 30 type of brooch; and

Fig. 9 is a sectional elevation taken on line 9—9 of Fig. 8.

Referring again to said drawing and particularly to Fig. 1 the supporting member 10 comprises a bar or strip 11 having the retaining pin 12 hinged at 13 on its under side and provided with any conventional type of catch 14.

The strip of the supporting member has grooves 15 on its under side and adjacent either 40 end, the purpose of which will be hereinafter described. The strip is further provided with two or more pins 16, on the upper side and spaced intermediate the grooves 15. The purpose of said pins will likewise be hereinafter described.

45 The ear clip 19 illustrated in Fig. 2 comprises an arcuate section 20 which may have any desired ornamentation thereon. Pivoted at 21 to the section 20 is the clip member 22. The clip member 22 is normally urged toward the sec-

50 tion 20 or held in a closed position by a spring 23 mounted on the pindle 22 in a conventional manner. The ear clip thus far described is of known construction.

The novel feature of the ear clip resides in a 55 spring tongue 24 formed from the body of the

clip member or suitably secured thereto. The width of the spring tongue is the same as that of the grooves 15 in the supporting member.

In securing the ear clips to the supporting member the spring tongues 24 are slipped into 60 the grooves 15 as shown in Figs. 6 and 7. They snugly engage the grooves and are thus firmly holding the ear clips on the supporting member forming part of an ornamental brooch later described. When it is desired to use the ear 65 clips as ear clips they are easily removed from the supporting member and the spring tongues 24 do not interfere in any manner when they are functioning as ear clips.

The ornamental bar 30 shown in Fig. 3 may be 70 formed of crystal or any other material lending itself to decoration. It may be of different cross sections and as illustrated is substantially circular in cross section with one side slabbed off. It is provided with two or more small 75 apertures or sockets 31, the number corresponding to the number of pins 16 on the supporting member.

The arrangement illustrated in Figs. 5, 6 and 7 show the ornamental bar 30 and ear clips 19 80 mounted on the supporting member 10 to form a brooch. The arcuate sections 20 of the ear clips are closed over the ornamental bar and the pins 16 cooperating with the apertures 31 prevent any longitudinal displacement of the 85 bar in relation to the supporting member. Thus it will be apparent that a very good looking bar pin or brooch may be formed of the supporting member, the ornamental bar and the ear clips.

The dress clip 40 comprises the front ornamental face 41 to which is pivoted at 42 with a conventional type of spring hinge, the clip member 43. Two or more bosses 44 are built up on the front section 41 and these bosses are provided with apertures or sockets 45 to accommodate the pins 16 on the supporting member. The bosses may also be provided with lips 46 thus forming a snug seat for the strip 11 of the 90 supporting member.

Figs. 8 and 9 illustrate the dress clip 40 mounted on the supporting member between the ear clips to form another distinctive style of brooch.

The dress clip and ear clips will naturally be 105 made up to harmonize with each other and thus the dress clip and ear clips may be worn separately and make an attractive appearance or as heretofore explained the ear clips and either the ornamental bar or the dress clip may be 110

mounted on the supporting member to form brooches.

Numerous changes may be made in details of construction by one skilled in the art without departing from the spirit of the invention or the scope of the appended claims.

I claim:

1. A supporting member for a piece of jewelry, said supporting member comprising a strip having grooves on one side adjacent its ends said grooves acting to prevent longitudinal movement of ornamental clips forming part of said piece of jewelry and adapted to cooperate with said grooves, a plurality of pins on the opposite side and means for securing said supporting member to a garment.

2. An ear clip forming part of an article of jewelry and comprising an arcuate section, a clip portion hinged to said arcuate section, and a spring tongue on said clip portion, said spring tongue acting as a means to secure said ear clip to a supporting member forming part of said article of jewelry.

3. A dress clip forming part of an article of jewelry, said dress clip comprising an ornamental front section, a clip member hinged to said front section, and bosses on said front section, said bosses being provided with apertures to accommodate pins on a supporting member for said article of jewelry.

4. An article of jewelry having in combination a supporting member, said supporting member having a strip with grooves on its under side adjacent the ends of said strip and pins on the upper side intermediate said grooves, a pair of ear clips, said ear clips comprising arcuate sections, clip portions hinged to said arcuate sections, and spring tongues on said clip portions, said spring tongues cooperating with

said grooves in said supporting member to position said ear clips on said supporting member, and an ornamental bar, said ornamental bar having a plurality of apertures to accommodate said pins on said supporting member.

5. An article of jewelry having in combination a supporting member, said supporting member having a strip with grooves on its under side adjacent the ends of said strip and pins on the upper side intermediate said grooves, a pair of ear clips, said ear clips comprising arcuate sections, clip portions hinged to said arcuate sections, and spring tongues on said clip portions, said spring tongues cooperating with said grooves in said supporting member to position said ear clips on said supporting member and a dress clip, said dress clip being adapted to be mounted on said supporting member between said ear clips and having sockets to accommodate said pins on said supporting member.

6. An article of jewelry having in combination a supporting member, a pair of ear clips adapted to be mounted adjacent the ends of said supporting member, means on the clip portion of said ear clips for securing said ear clips to said supporting member, and an ornamental bar adapted to be enclosed by said ear clips on said supporting member and provided with means for preventing longitudinal movement of said bar in relation to said supporting member.

7. An article of jewelry having in combination a supporting member, said supporting member comprising a strip provided with grooves running at right angles to the length of said strip and ornamental clips having means on the clip portion thereof to cooperate with said grooves and thereby position said ornamental clips on said supporting member.

LOUIS MAZER.
